UNITED STATES PATENT OFFICE.

AUGUSTIN DUBOCE, OF SAN FRANCISCO, CALIFORNIA.

ADVERTISING APPARATUS.

SPECIFICATION forming part of Letters Patent No. 379,105, dated March 6, 1888.

Application filed October 1, 1887. Serial No. 251,262. (No model.)

To all whom it may concern:

Be it known that I, AUGUSTIN DUBOCE, of the city and county of San Francisco, State of California, have invented an Improvement 5 in Advertising Apparatus; and I hereby declare the following to be a full, clear, and exact description of the same.

My invention relates to that class of devices, especially of an optical nature, which are designed for attracting the attention for purposes of amusement, or more particularly for advertising; and my invention consists, in connection with suitable reflecting surfaces or mirrors and distorting glasses, of a rotary 15 sign placed in such relation thereto as to have its figures, letters, and other characters thereon reflected and presented in a variety of positions and movements, plain and distorted.

20 My invention also consists in the novel mechanism by which the design is moved, and, finally, in the combination of a lamp or other source of light and reflecting surfaces with a rotating shade over the lamp or other source of light, 25 and provided with designs upon its surface, which are reflected in the mirrors and presented through the glasses, all of which I shall hereinafter fully describe by reference to the accompanying drawings, in which—

30 Figure 1 is an elevation of my apparatus. Fig. 2 is a horizontal section on the line $x\ x$. Fig. 1. Fig. 3 is an elevation showing the propelling mechanism. Fig. 4 is an elevation of a modification of the propelling mechanism.

35 A is a frame of suitable character which supports the lamp B.

C is the shade for the lamp, which here represents any cylinder or frame which is supported over it, and has imparted to it a rotary motion in a manner and by a mechanism 40 which I shall presently describe. Upon the surface of this shade is depicted a variety of figures, designs, and letters of an amusing, instructive, and advertising nature.

45 Supported by the frame A and back of the shade of the lamp are the curved reflecting surfaces or mirrors D. These are so arranged as to reflect the designs on the moving shade, so that they can be seen from the front. The 50 mirror on the left hand I prefer to have with

a smooth surface, while that on the right hand I prefer to have with a broken, bent, or corrugated surface in such a way that the figures upon the shade will be reflected double, the smooth-surfaced mirror on the left reflecting 55 them single, but magnifying them to a small extent. In order to give the lower portion or feet of the figures an apparent motion, I make in the mirrors small inequalities d , and to heighten the effect I secure or paint on the 60 surface of the mirrors a railing, (represented by d'), both being in such a position that the feet of the figures will be reflected in the inequalities and through the railing, and will be given a seeming motion, as in walking or running. 65 The pattern on the shade is also reflected in a variety of curious and interesting ways.

To the front of the frame, and just in front of the shade, is secured a glass, E, the surface of which is corrugated, and the design on the 70 shade appearing through this corrugated glass is seen with a curious effect of a wavy motion, which is fully described in my Patent numbered 317,926, dated August 24, 1886. Across the center of this glass (here placed behind it) is 75 a second corrugated glass, e, the corrugations of which meet those of the glass E at an angle, so that the feet of the figures seen through the double glass seem to be moving; and to heighten this effect I have a railing, e' , on the 80 double glass.

I may inclose the entire shade, though I have herein shown the base of the shade as completely exposed, and on this lower portion I place the advertising characters, the upper 85 portion of the shade being more for the purpose of attracting and keeping the attention for a few moments.

F are shields on each side of the shade and extending from the edges of the front glass. 90

Now, in order to make the shade rotate with a constant though slow movement, I have the following propelling mechanism: Secured to the frame of the lamp is a standard, g, the upper end of which is bent inwardly and is provided with a bearing-point, G. From the standard extends an arm, H, the end of which is bent over the top of the lamp-chimney and has stepped in its top a shaft, I, which carries a winged wheel, i, which is directly over the 95 100

lamp-chimney. In the center of the top of the shade is supported a bearing, J, which fits on the bearing-point G of the main standard, and around said bearing is a ring or annular hub, 5 K, on the inner surface of which the upper end of the shaft I bears, said upper end being somewhat enlarged to make a kind of roller. The hub K may be provided with wings or blades L to assist in the effect, though they are not 10 absolutely essential.

The operation of this propeller is as follows: The winged wheel i, being directly over the chimney of the lamp, is caused to rotate by the uprising draft, thereby rotating the shaft 15 I, to which it is affixed, and the end of the shaft rolling on the inner surface of the annular hub or ring K causes, through friction, the rotation of said hub, thereby rotating the shade. While the motion of the winged wheel 20 is comparatively rapid, the motion of the shade is much slower, as its movement is due entirely to the friction of the end of the shaft I on its hub. This motion, however, is adapted for the purpose of the apparatus, 25 giving the observer full opportunity to inspect the designs. The primary rotation of the winged wheel being due to a draft, it is immaterial by what means I create said draft. Therefore, although I have herein described the draft 30 as occasioned by a rising current of heated air from the lamp, I do not confine myself to this, as I may arrange the parts, as shown in Fig. 4, entirely outside of and above the rotating cylinder or shade, the winged wheel being driven 35 by a draft through the pipe M, which corresponds to the lamp-chimney, and by this arrangement the cylinder may be driven in the day-time without employing any light.

I am aware that it is not new to communicate motion by means of a wheel deriving rotation from an uprising current of heated air; but in my case the motion is not derived directly, but is obtained through the frictional contact of the wheel-shaft with the hub of the 45 shade.

I do not confine myself to making the apparatus in exactly the form herein described—namely, the form of a lantern or lamp provided with a shade—for I may have an ordinary cylinder fitted over a suitable source of light—such, for example, as a gas-jet—which will also give heat enough to cause its rotation. However, in the form I have described I deem it to be advantageous for the purposes in view.

55 I am aware of the existence of a rotary lantern surrounded by reflectors, and I do not claim such, broadly.

Having thus described my invention, what I claim as new, and desire to secure by Letters 60 Patent, is—

1. In an advertising apparatus, the combination of a rotating frame having depicted upon its surface designs, letters, and characters of suitable description, a fixed frame, a 65 magnifying-reflector mounted in said fixed frame and placed behind the rotating frame on one side, and a duplicating-reflector mounted

in said fixed frame and placed behind the rotating frame on the other side, substantially as described.

2. In an advertising apparatus, a rotating cylinder or frame provided on its surface with designs, patterns, letters, characters, &c., in combination with a fixed frame having reflectors placed behind and located on each side 75 of the rotating frame, and a corrugated or uneven surfaced glass mounted in the fixed frame in front of the rotating cylinder or frame, substantially as described.

3. In an advertising apparatus, a rotating cylinder or frame having designs, figures, &c., depicted upon it, in combination with reflectors mounted in a fixed frame and encircling the rotating cylinder or frame, said reflectors having inequalities made in them, whereby a 85 portion of the designs or figures is given the appearance of moving, substantially as described.

4. In an advertising apparatus, a rotating cylinder or frame having designs, figures, &c., 90 depicted upon it, in combination with encircling reflectors mounted in a fixed frame and having inequalities made in them, and a railing representation on their surfaces, whereby a portion of the designs or figures is given 95 the appearance of moving behind said railing, substantially as described.

5. In an advertising apparatus, a rotating cylinder or frame having designs depicted upon its surface, in combination with a fixed frame having a magnifying-reflector placed behind and to one side of the rotating cylinder or frame, a duplicating-reflector mounted in said fixed frame on the opposite side of the rotating cylinder or frame, and a distorting-mirror at the front of the rotating cylinder or frame, substantially as described.

6. In an advertising apparatus, a fixed lamp or light and a shade rotating about it and having depicted upon its surface designs, patterns, and characters, and reflectors mounted in a fixed frame and placed about said shade on opposite sides, whereby its designs are seen directly and indirectly, substantially as described.

7. In an advertising apparatus, a fixed lamp and its shade having depicted upon its surface designs of suitable character, and a propeller at the top of the lamp, whereby the shade derives a rotary motion from the uprising heated current of air from the lamp, in combination with reflectors and glasses placed about the shade on opposite sides for the purpose of exhibiting its designs, substantially as described.

8. In an advertising apparatus, a cylinder 125 or frame carrying the matter to be advertised, in combination with the propelling mechanism, whereby it is given a rotary motion, consisting of a wheel mounted in a draft and having a shaft, and a ring or hub carried by the 130 cylinder or frame, and against which the wheel-shaft rolls in frictional contact, substantially as herein described.

9. In an advertising apparatus, the lamp

and the shade carrying the matter to be advertised, in combination with the means for rotating the shade, consisting of the wheel over the lamp, whereby it is given a rotary motion, 5 the shaft on which the wheel is mounted, the hub or ring, against the surface of which the shaft rolls in frictional contact, and the wings or blades on said hub, substantially as herein described.

10 10. An advertising apparatus comprising the lamp and the shade surrounding the lamp and having designs depicted upon its surface, the propeller for rotating the shade, consisting of the wheel moved by the draft, the shaft

on which the wheel is mounted, and the annular hub or ring in the top of the shade and on which the shaft rolls in frictional contact, the magnifying and duplicating reflecting surfaces or mirrors behind and on each side of the shade, and the distorting glasses in its front, 15 20 all arranged and adapted to operate substantially as herein described.

In witness whereof I have hereunto set my hand.

AUGUSTIN DUBOCE.
